LOOM

Atwood V. Pullins, Kansas City, Mo., assignor of
one-half to Charles Hipsh, Kansas City, Mo.

Application December 30, 1937, Serial No. 182,486

7 Claims. (Cl. 139—29)

This invention relates to looms, particularly to those of the hand operated type, and has for its principal object to provide a loom of this character capable of high speed and accurate operation for economically producing a high quality fabric of uniform weave.

Other important objects of the invention are to provide the loom with a positive control for regulating movement of the beater whereby the 10 weft threads are all beat up to a positive forward point at the fell of the cloth with the same degree of spacing, effecting a definite number of weft threads per inch; to provide means for maintaining uniform tension on the warp; to provide a throwing mechanism for actuating the shuttle which is readily synchronized with movement of the beater and heddles to permit a substantially rhythmic operation; and to provide the 15 loom with an improved harness for suspendingly actuating the heddles.

In accomplishing these and other objects of the invention, as hereinafter pointed out, I have provided improved details of structure, the preferred form of which is illustrated in the accompanying drawings, wherein:

Fig. 1 is a longitudinal section through a loom embodying the features of the present invention.

Fig. 2 is a cross-section through the loom on the line 2—2 of Fig. 1.

Fig. 3 is a side elevational view of the end of the loom which supports the cloth beam roll and particularly illustrating the take-up mechanism therefor, and its connection with the beater.

Fig. 4 is a detail plan view of the cloth beam roll driving mechanism.

Fig. 5 is a detail view of the ratchet, ratchet operating pawl, and click for controlling take-up operation of the cloth beam roll in synchronism with the beater.

Fig. 6 is a detail perspective sectional view through the beam roll upon which the warp threads are wound, and particularly illustrating the brake mechanism which cooperates with the cloth beam roll actuating mechanism in maintaining uniform tension on the warp.

Fig. 7 is a fragmentary horizontal section through the loom on the line 7—7 of Fig. 1.

Fig. 8 is a detail perspective view of one of the cross heads and its guide for operably connecting the beater with the controlling mechanism for maintaining a constant amplitude of movement for the beater.

Fig. 9 is a horizontal section through the control mechanism on the line 9—9 of Fig. 1.

Fig. 10 is a detail perspective view of the stationary and movable members of one of the beater control mechanisms.

Fig. 11 is an enlarged perspective view of one of the rollers carried by the movable member and engageable with the fixed member of the control mechanism.

Fig. 12 is an enlarged detail perspective view of the shuttle box end of the shuttle track, particularly illustrating one of the pickers for effecting 10 throw of the shuttle along the shuttle track.

Fig. 13 is a cross-section on the line 13—13 of Fig. 12, particularly illustrating mounting of the picker.

Fig. 14 is a fragmentary side elevation of one 15 of the picker guides, particularly illustrating the spring for forming a bumper to limit movement of the picker and for effecting throw of the shuttle.

Fig. 15 is a detail perspective view of one of the 20 heddles.

Fig. 16 is a detail perspective view of the ratchet pawl, its operating lever for actuating the cloth beam roll, and the pawl throw-out lever.

Fig. 17 is a detail section on the line 17—17 of 25 Fig. 7.

Referring more in detail to the drawings:

1 designates a loom constructed in accordance with the present invention and which includes 30 a frame 2, having side members 3 and 4 each including a horizontal beam 5 supported on legs 6 and 7 spaced from the ends thereof as best shown in Fig. 1. The side members 3 and 4 are connected by a base frame 8 attached to the lower ends of the legs 6 and by cross bars 9 connecting the upper ends of the legs and the horizontal beams 5, as shown in Fig. 1. The rear ends of the horizontal beams are also connected by a cross bar 10 over which the warp threads are drawn as later described. Carried by the base frame 8 is a vertical post 11 supporting a weaver's seat 12 at a point substantially midway between the side frames. Rotatably journaled in suitable brackets 13, carried by the legs 7, is a shaft 14 supporting a warp beam 15. The warp beam 15 includes disks 16 fixed to the shaft 14 and carrying a circular series of bars 17 that are attached to the peripheries of the disks to form an open cylinder or drum. The bars 17 are provided along 50 the length thereof with spaced pins 18 to separate the warp threads 19 which may vary in color depending upon the pattern being woven into the cloth.

At each end of the drum is provided a space 55

for brakes 20, each including a cable 21 extending around the periphery thereof and having one end attached to an adjustable eye bolt 22 carried by a bracket 23 projecting from the cross bar 9 5 and its opposite end connected with a tensioning spring 24 that is anchored to a cross bar 25 adjustably secured to the leg 7 by selectively attaching it to one of a series of pins 26 projecting forwardly from the edges of the legs as 10 shown in Fig. 6. By adjusting the bar 25, on selected pairs of pins, tension of the spring 24 is varied to vary braking action of the cable on the roll.

The warp threads extend upwardly over the 15 bar 10 and forwardly of the machine through heddles 27 and 28, through a reed (later described), over a cloth beam roll 29, and over a padded roll 30. The roll 29 extends transversely of the frame adjacent the front ends of the beam 20 5 and has its shaft 31 journaled in ball bearings 32 carried by the side frames. The roll 30 is carried on arms 33 that are swingingly mounted on pivots 34 at a point below the roll 29. The opposite ends of the arms are provided with 25 notched seats 35 to removably mount the ends of the shaft 36 carrying the roll 30. The roll 30 is retained in yielding contact with the roll 29 by coil springs 37 having one end attached to the beams 5 and their opposite ends to the arms 30 as best shown in Figs. 1 and 4. The roll 29 is preferably covered with a non-slip material, such as sandpaper or the like 38, to prevent slippage of the woven cloth in holding tension on the woven cloth and warp threads. One end of the shaft 35 31 projects through the outer side of the adjacent beam 5 and carries a gear 39 that meshes with an idle gear 40 that is rotatably mounted on a stub shaft 41 adjustably positioned in an arcuate slot 42 of a supporting plate 43, the supporting 40 plate being attached to the outer side of the frame and spaced therefrom as shown in Fig. 4. Fixed in driving relation with the gear 40 is a larger gear 44 that meshes with a driving gear 45 on a ratchet gear shaft 46 rotatably mounted 45 in the plate 43. Also fixed on the shaft 46 on the side thereof adjacent the beam 5 is a ratchet wheel 47 having teeth 48 adapted to be engaged by a pawl 49 and a click 50 to respectively effect 50 advance rotation of the ratchet gear and prevent retracting rotation thereof under pull of the woven cloth and warp threads.

The pawl 49 has a hook-shaped upper end 51, and has its lower end fixed to a block 52 pivotally mounted on an actuating lever 53. The lever 53 55 is pivoted at one end, as at 54, on the beam 5 and has its opposite end extending rearwardly of the machine and is connected with the beater 55 by link and arm connections 56 and 57. The pawl is retained in yielding contact with the teeth 60 of the ratchet wheel by a spring 58, having one end attached to a pin 59 depending from the pivoted end of the lever 53 and its opposite end to a pin 60 depending from the block 52. The pawl 49 may be selectively moved away from the ratchet 65 wheel by means of a lever 61 pivotally supported in a clamp block 62 attached to the under side of the beam 5, and which has an actuating arm 63 provided with a lateral handle 64 projecting toward the weaver's seat. The lever 61 carries a laterally extending finger 65 for engaging the side of the pawl opposite to the spring 58. It is thus apparent that when the lever 63 is swung retractively, the finger 65 moves 70 the pawl out of engagement with the ratchet 75

teeth to disconnect it from driving relation with the ratchet wheel.

Extending upwardly from the beam 5, at a point about midway between the legs 6 and 7, are uprights 66, carrying a cross bar 67 at their opposite ends to suspend a heddle carrying frame 68. The frame 68 includes upper and lower bars 69 and 70 connected at the ends by vertical bars 71 and 72. The frame 68 is adjustably suspended from the bars 67 on rods 73 and 74 extending loosely through openings 75 in the cross bar and carrying wing nuts 76 engaging the upper side of the bar. The depending ends of the rods extend through aligning openings 77 in the bar 69 and carry wing nuts 78 and 79 engaging the upper and lower sides of the bar 69 to rigidly connect with the frame. Carried by the lower bar 70 of the frame, are spaced heddle frame supporting stops 80 to support the heddles in their lowermost positions.

The heddle frames 27 and 28 are of conventional construction and include rectangular frames 83 and 84 carrying the heddles 85 through which the warp threads are passed as in conventional loom practice. The heddle frames are suspended from a horizontal shaft 86, having its ends journaled in bearing blocks 87 and 88 carried on the lower ends of rods 89 and 90 having their upper ends extending through suitable openings 91 in the bar 69 and through aligning 30 openings 92 in the bar 67 to be connected therewith by wing nuts 93 and 94 engaging the upper and lower sides of the bar 67, as best shown in Fig. 2. The heddle frames are suspended from the shaft 86 at the respective ends of cables 95 35 and 96 which extend through openings 97 and 98 in the shaft, the ends of each cable being connected with eyes 99 and 100 on the heddle frames. The heddle frames are alternately raised and lowered by means of treadles 101 and 102 that are 40 pivoted, as at 103, to blocks 104 carried by the base frame 8 at a point below the weaver's seat 12. The treadles carry pedal blocks 105 and 106 to be engaged by the weaver's feet. The free ends of the treadles are pivotally connected with 45 the respective heddle frames by rods 107 and 108 extending through suitable openings 109 in the lower cross bar of the frame 68.

The heddles in one frame are staggered relatively to the heddles in the other frame, and they 50 are provided with eyes 110 to pass the warp threads, alternate warp threads being engaged by the heddles in one frame and extending between the heddles in the other frame so that they are divided into two sets, one set being actuated by one treadle and the other set by the other treadle. Thus, when the weaver presses one of the two treadles, one of the heddle frames is raised and with it one set of warp threads to effect 55 decussation or crossing of alternate warps to form a shed through which the shuttle is passed as later described.

The beater 55 includes a rectangular frame having a lower cross bar 111 that is connected with the back of the base frame 8 by hinges 112 65 as best shown in Figs. 2 and 3. Fixed to the ends of the lower bar 111 are uprights or swords 113 which extend between the heddle supporting frame and the cloth beam roll, previously described, and their upper ends are connected by 70 means of a handle bar or hand rail 114 that is adapted to be grasped by the weaver to effect oscillation of the beater as later described.

Carried by the uprights 113, at a point below the hand rail, is a shuttle track 115 having its 75

ends projecting through notches 116 and 117 cut in the upper edges of the beams 5 to carry shuttle guides 118 and 119 best illustrated in Fig. 12, the guides being formed by spaced flanges 120 and 121 projecting upwardly on opposite side edges of the shuttle track and which are provided with slots 122 and 123 to accommodate guide rods 124 and 125 having their ends supported at the ends of the slots. Slidably mounted on the guide rods 10 are pickers 126 for one set of guides, and a picker 127 for the other sets of guides. The pickers each include a block 128 having ends freely movable in the slots of the guides and provided with openings 129 for passing the guide rods. Fixed on each 15 of the blocks, intermediate the ends thereof, is a bumper pad 130 for engaging the ends of the shuttle 131, later described. Also fixed to the center of each block, in aligning relation with the pads, are guards 132 having forwardly and upwardly curved ends 133 to catch the shuttle when it is propelled from one end of the track to the other.

The pickers are operated by a shuttle throwing mechanism 134 including cords 135 and 136 extending through openings 137 in the respective guide blocks and which are secured thereto by knotting the ends as indicated at 138. The cord 135 is threaded through pulley blocks 139 and 140 carried by the cross bar 67, with the pulley 140 25 located substantially midway of the loom. The cord 136 is threaded over a pulley 141, located in substantially the same spaced relation from the side of the loom as the spacing of the pulley 139. The free ends of the cord depend from the 30 pulleys 140 and 141 and are connected by a D-shaped handle 142 adapted to be grasped by the hand of the operator and swung from side to side with a downward movement to effect alternate actuation of the pickers in synchronism with oscillation of the beater and movement of the heddles. The shuttle is of standard construction and contains a cop on which the weft threads are wound, as in conventional practice. In order to absorb the shock of the pickers when they are 35 drawn to the inner ends of the guides, the guide rods are provided with coil springs 143 and 144 having one end engaging the ends of the slots and their opposite ends engaging washers 145 on the rods to be engaged by the respective picker blocks. Carried upon the shuttle track, and projecting 40 upwardly therefrom, is a reed 146 for engaging and beating home the weft as the weaving progresses. The hand rail 114 has a groove 150 in its lower edge to cooperate with seating grooves 55 151 and 152 in the shuttle race track and a clamping bar 153 to mount the reed.

As above pointed out, it is one of the important objects of the present invention to provide a better quality of cloth by compaction of the weft 60 responsive to controlling amplitude of movement of the beater. It is, therefore, necessary that all of the strokes of the beater be exactly of the same length and to effect this control, the beater is connected with control mechanisms 156 and 157, each including disks 158 fixed to the ends of a shaft 159 that extends transversely of the machine, back of the beater, and which is indirectly supported by brackets 160 and 161 that are attached to the cross bar 9, previously described. 65 The disks are spaced from the brackets to accommodate fixed disks 162 that are rigidly attached to the brackets by fastening devices, such as cap screws 163. The disks 162 have laterally extending annular flanges 164 encircling a central hub 165 to form inner and outer races 166 and 167

engaged by inner and outer sets of rollers 168 and 169. The rollers 168 and 169 are carried on antifriction bearings 170 supported on stub shafts 171 having eccentrically positioned threaded shanks 172 extending through openings 173 in the rotary disks as shown in Fig. 9. The ends of the stub shafts 171 form shoulders 174 for engaging the outer sides of the rotary disks, and which cooperate with nuts 175 that are threaded onto the shanks to rigidly retain the shafts in 10 adjusted position on the rotary disks to keep the rollers in rolling contact with the respective tracks, and thereby eliminate play incidental to thrust of the connecting pitmans. The hubs 165 are of sufficient inner diameter to freely pass 15 the shaft 159 so that the shaft and rotary disks are directly carried by the rollers in bearing contact with the tracks. In case wear occurs between the rollers and their tracks, play is removed by adjusting the stub shafts relatively to their eccentric mounting. This is accomplished by loosening the nuts and turning the shafts by means of a suitable tool insertable in fixed openings 176 in the stub shafts so that they may be rotated to bring the rollers into snug engagement with the 20 tracks. After the adjustment, the nuts are again tightened to retain the shafts in adjusted position.

The rotary disks carry wrist pins 177 that mount antifriction bearings 178 that are seated in 25 suitable openings 179 formed in the ends of pitmans 180, having their opposite ends provided with similar antifriction bearings 181 that are mounted on pins 182 projecting from a cross head block 183 having openings 184 for slidable mounting upon guide rods 185 and 186. The guide rods 185 and 186 have their ends fixed within supporting blocks 187 and 188 attached to the inner faces of the beam 5, as best shown in Fig. 7. Connected with the cross head blocks 183, by means of connecting bars 189 are similar cross head blocks 190 carrying pins 191 having antifriction bearings 192 seated within openings in the ends of links 193. The opposite ends of the links connect by means of a similar antifriction bearing 194 with pins 195 projecting laterally from the side members 113 of the batten frame.

With the construction thus described, it is obvious that the rotary disks are retained for rotation about a fixed axis and that due to the rolling contact of the rollers in engaging relation with the inner and outer races of the fixed disks, there is very little friction and they have entirely free rotation to avoid dead center positions.

With the eccentric arrangement, the beater is caused to dwell for a greater length of time at the rear of its stroke than at the forward end of its stroke to give sufficient time for the operator to throw the shuttle through the shed that is formed in the decussation of the warp threads. The rotary disks are also constructed so that they are heavy enough to act as fly wheels giving a smooth action to the movement of the beater. In order to prevent longitudinal play of the shaft 159 it is provided with spaced collars 196 and 197 engaging the respective sides of an antifriction bearing 198 that is carried on a bracket 199 which is fixed to the cross member 9.

In operating a loom constructed and assembled as described, and assuming that the warp threads are threaded through the eyes of the heddles and through the dents of the reed to extend over the rolls 28 and 30, the weaver positions herself on the seat 12 with the right and left feet respectively engaging the pedal blocks of the treadles, the left

hand grasping rail 114 and the right hand the handle 142 of the shuttle throwing mechanism. With one treadle depressed and the other in its upper position, the alternate warp threads are spread apart to form the shed above the shuttle race, as shown in Fig. 1. Then, by giving the handle a sharp jerk with a slight swinging motion in the direction that the shuttle is to be propelled, the shuttle is driven by the engaged picker 10 between decussated warp threads to the opposite end of the shuttle track where it is stopped by the picker. The beater is then swung forward in the direction of the weaver to beat up the weft thread that has been deposited by the shuttle 15 in the shed formed by spreading of the warp threads. The treadles are then alternately operated to reverse spreading of the sets of warp threads, whereupon the shuttle is again driven through the shed over the shuttle track to lay a 20 weft thread in the shed of the warp. The beater is again drawn forward to beat up the deposited weft. Since the beater can only be moved to a fixed point relatively to the fell of the cloth, all of the weft threads are drawn up to the same degree and have uniform spacing. During actuation of the beater, the roller 29 is operated to effect movement of the cloth. This is effected through the arm 57, link 56, pawl lever 53, and pawl 50 to move the ratchet wheel 47. Movement 25 of the ratchet wheel operates gears 45, 44, 39 and 38 to effect corresponding movement of the roll 29. Feed of the cloth may be adjusted by applying gears 45 of different diameter on the shaft 46. When this adjustment is made, the shaft 41 is 30 positioned in the arcuate slot 42 to accommodate the larger size gear. Reciprocation of the beater is controlled by reason of the eccentrically mounted wrist pins on the rotary disks and their rotation about the fixed axis of the cooperating disk members which carry the bearing race tracks. 35 Therefore, all of the weft threads are beat up the same distance to maintain uniform spacing of the weft threads as above noted.

From the foregoing it is obvious that I have 40 provided a loom which is capable of high speed and accurate operation for economically producing a high quality fabric of uniform weave, the latter being effected by maintaining constant tension on the warp threads and by effecting an 45 exact degree of spacing imparted to each weft thread incidental to controlled movement of the beater.

What I claim and desire to secure by Letters Patent is:

55 1. In a loom, a beater, means oscillatably supporting the beater, control means for the beater including a rotary member, inner and outer annular race tracks, means for rigidly supporting the race tracks on the loom, inner and outer sets of rollers on the rotary member engageable with the respective race tracks, and eccentric means connecting the rotary member with the beater.

60 2. In a loom, a beater, means oscillatably supporting the beater, control means for the beater

including a rotary member, inner and outer annular race tracks, means for rigidly supporting the race tracks on the loom, inner and outer sets of rollers on the rotary member engageable with the respective race tracks, a cross head guide, interconnected cross heads on the guide, a wrist pin on the rotary member, a pitman connecting one of the cross heads with the wrist pin, and a link connecting the other cross head with the beater. 5

3. In a loom, a beater, means oscillatably supporting the beater, control means on the beater including a rotary member, a supporting member having inner and outer annular race tracks, inner and outer sets of rollers having adjustable support on the rotary member and engageable with the respective race tracks, and eccentric means connecting the rotary member with the beater. 10

4. In a loom, a beater, means oscillatably supporting the beater, control means for the beater including a pair of rotary members, inner and outer annular race tracks associated with the respective rotary members, means for rigidly supporting the race tracks on the loom, inner and outer sets of rollers on the rotary members engageable with the respective race tracks, means interconnecting the rotary members, and eccentric means connecting the rotary members with the beater. 15

5. In a loom, a beater, means oscillatably supporting the beater, control means for the beater including a pair of rotary members, inner and outer annular race tracks associated with the respective rotary members, means for rigidly supporting the race tracks on the loom, inner and outer sets of rollers on the rotary members engageable with the respective race tracks, cross head guides, interconnected cross heads on the guides, crank means on the rotary members, pitmans connecting one of the cross heads of each guide 20 with the crank means, and links connecting the other cross heads of each guide with the beater. 25

6. In a loom, a beater, means oscillatably supporting the beater, control means for the beater including a rotary member and a stationary member, inner and outer annular race tracks on one of said members, inner and outer sets of rollers on the other member engageable with the respective race tracks, and eccentric means connecting the rotary member with the beater. 30

7. In a loom, a beater, means oscillatably supporting the beater, control means for the beater including rotary and stationary members, inner and outer annular race tracks on one of said members, inner and outer sets of rollers on the other member engageable with the respective race tracks, a cross head guide, interconnected cross heads on the guide, a wrist pin on the rotary member, a pitman connecting one of the cross heads with the wrist pin, and a link connecting the other cross head with the beater. 35
